UNITED STATES PATENT OFFICE.

EDWIN H. COLPITTS, OF EAST ORANGE, NEW JERSEY, ASSIGNOR, BY MESNE ASSIGNMENTS, TO WESTERN ELECTRIC COMPANY, INCORPORATED, A CORPORATION OF NEW YORK.

CONTROL DEVICE FOR WIRELESS SIGNALING.

1,198,700.

Specification of Letters Patent. Patented Sept. 19, 1916.

Application filed September 16, 1915. Serial No. 50,966.

To all whom it may concern:

Be it known that I, EDWIN H. COLPITTS, a subject of the King of Great Britain, residing at East Orange, in the county of 5 Essex and State of New Jersey, have invented certain new and useful Improvements in Control Devices for Wireless Signaling, of which the following is a full, clear, concise, and exact description.

10 This invention relates to the control for signaling purposes of the large current obtained from the output circuit of a thermionic amplifier.

The object is to reduce the power consumption to a minimum or small value and to obtain a maximum output from a given amount of apparatus. The results are obtained by so arranging the circuit that the space current flows in the amplifier tubes 20 only during the time that signal impulses are being sent. This might be accomplished by making and breaking the output or high power circuit of the amplifier, but this involves the interruption or breaking of a 25 circuit in which a large current at a high potential may be flowing. The desired result can be obtained better by an arrangement by means of which the voltage of the battery in the input or grid circuit has such a 30 value that the space current, that is, the current in the output circuit, is made very small. In other words, provision is made whereby the voltage applied to the grid or input circuit of the amplifier is changed 35 at the instant of signaling from such a value as causes a minimum energy loss in the output circuit to a value which permits of normal flow of current in the said circuit. This may be accomplished in a variety of ways 40 and very readily for the reason that the normal power absorbed in the input circuit of a thermionic amplifier is very small.

Figure 1 of the drawing shows one arrangement of circuits by which the desired 45 result is obtained; Fig. 2 shows a modified circuit.

Referring to the figures, 1 represents an inductance deriving high frequency oscillations of low power in a manner hereafter 50 described and which is connected to the input circuit of a thermionic amplifier 3; the electrode 5 of said amplifier being the heated element and the electrode 4 being the usual grid. The output circuit is connected from 55 the plate electrode 6 through the tuning con-

denser 2, the inductance 8 and the filament 5. In parallel to the inductance 8 is the power battery 7 and choke coil 24. For signaling purposes, the inductance 8 is inductively connected to the inductance 9 60 which, in turn, is connected to the signaling system. This signaling system may consist of any wire system or of a radiating antenna to be used for space telegraphy as shown in the figures, in which 10 represents the elevated antenna or other suitable radiating system and 11 represents the usual earth connection for such a system.

Connected to the input terminals of the amplifier and in parallel to the circuit containing the inductance 1, is a circuit containing a battery 12, which is the usual battery for determining the potential applied between the electrodes 4 and 5. In this invention, battery 12 has a sufficiently high 70 voltage to reduce the space current flowing between the electrodes 6 and 5, from the battery 7, to zero or to a relatively small value. In order to transmit signaling currents, it is necessary to reduce the voltage impressed 75 on the input circuit sufficiently to permit the flow of the normal space current. In order to accomplish this the following arrangement is used: A switch or key 13 is placed in the circuit of the battery and a large 80 resistance 14 of several thousand ohms or more is placed in shunt to this key. A conductor 15 leads from some intermediate point 16 of the battery 12, the free end of 85 said conductor 15 being placed in juxtaposition to the spring terminal 17, which also 90 forms one terminal of the switch 13.

It has been found desirable also, but not necessary, to place a key or switch 18 in the circuit of the inductance 1. The compound 95 key or switch may be operated by hand directly or indirectly by means of the magnet or relay 19. The armature 20 is rigidly secured to the operating portions of the switch. This relay 19 may, in turn, be operated by means of the key 21 which closes 100 a circuit containing the said key, battery 22 and the winding of the relay. In the circuit of the inductance 1 is placed a condenser 23. A choke coil 24 is placed in series with the battery 7. A similar choke coil 25 is placed in the circuit of the battery 12.

The operation of the system is as follows: 110 When no signals are being transmitted the

switch 13 is closed, thereby short-circuiting the high resistance 14 and permitting the voltage of the whole battery 12 to be impressed on the input circuit of the amplifier. 5 This battery is of sufficient voltage to prevent the flow of space current between the electrodes 5 and 6. Upon closing the key 21, the switch 13 is opened and the member 17 is removed to make contact with the terminal 26 and also to close the switch at 10 18. This operation brings the point 16 of the battery 12 into electrical connection with the terminal 4 of the amplifier. Conductor 15 is placed at such a point 16 of the battery that the voltage which is now impressed on the input circuit of the amplifier is sufficiently small to permit the normal flow of space current through the amplifier. At the same time the closing of 15 the switch 18 permits the transfer of high frequency low power oscillations from the output circuit into the input circuit of the amplifier by means of the inductance 1. The whole operation results in a flow of 20 amplified high frequency oscillations in the output circuit of the amplifier. The output circuit containing the condenser 2 and inductance 8 is tuned to the frequency of the radiating antenna system. The frequency 25 of this circuit 2-8 and the antenna determine the period of the high frequency oscillations which are to be transmitted, and of the oscillations which are fed back into the input circuit by means of the inductance 1.

The purpose of the resistance 14 is to prevent that portion of the battery 12 which is not used when signaling from being short-circuited. The condenser 23 is to prevent the discharge of the battery 12 through the inductance 1, and the choke coils 24 and 25 are inserted in order to prevent the passage of high frequency oscillations through the battery circuits.

45 In Fig. 2 a modification of the output circuit is shown. In this case the battery 7 is connected in series instead of in parallel to the inductance 8, and the frequency of the oscillations to be radiated, as well as 50 the frequency of the oscillations fed back to the input circuit by means of the inductance 1, is determined chiefly by the period of the radiating antenna. In this modification battery 7 is shunted by a condenser 28, 55 which condenser affords a path of low impedance around the battery 7 for the high frequency oscillations, and also forms a short circuit for transient high frequency disturbances developed in the battery 7.

60 The connection for the remainder of this system is precisely as shown in Fig. 1.

In the specification and drawing two methods of determining the period of the oscillations in the output circuit, and 65 therefore in the feed-back circuit, have been

shown, but it is to be understood that any other suitable method of tuning this output circuit can be used equally well. Also, it is to be understood that while only one amplifying tube has been shown, in general 70 such a single tube will not supply sufficient power for radio telegraphy, and that therefore in general it will be desirable and necessary to have a plurality of such tubes connected in parallel in any suitable manner, such, for example, as shown in patent 75 to Arnold No. 1,129,943 of March 2, 1915.

It is obvious that the method is not limited to simple hand sending but can be employed wherever the sending of signals involves an interrupted output.

What is claimed is:

1. In a high frequency signaling system; a thermionic amplifier of the audion type, a source of voltage connected to the input circuit of said amplifier; a circuit deriving high frequency oscillations of a low power from the output circuit of said amplifier, said circuit being connected to the input circuit of the amplifier, and means adapted to 85 vary the amount of voltage of the said source impressed upon the input circuit of the amplifier whereby the space current is reduced to a small value when not signaling.

2. In a high frequency signaling system; 90 a thermionic amplifier of the audion type; a circuit inductively connected to the output circuit of said amplifier for deriving high frequency oscillations of low power from the output circuit of said amplifier, said circuit 100 being connected to the input circuit of the amplifier; a battery connected to the input circuit of said amplifier and a switch for varying the amount of the battery voltage impressed upon the input circuit of the 105 amplifier whereby the space current is reduced to a minimum or small value when not signaling.

3. In a high frequency signaling system; 110 a thermionic amplifier of the audion type; a circuit inductively connected to the output circuit of said amplifier for deriving high frequency oscillations of low power from the output circuit of said amplifier, said circuit being connected to the input circuit of the 115 amplifier; a battery connected to the input circuit of said amplifier, said battery having sufficient voltage to reduce the space current of the amplifier to a minimum or small value and signaling means for reducing the battery voltage impressed on the input circuit of the amplifier when signaling, to permit a 120 large space current.

4. In a high frequency signaling system; 125 a thermionic amplifier of the audion type; a circuit inductively connected to the output circuit of said amplifier for deriving high frequency oscillations of low power from the output circuit of said amplifier, said circuit being connected to the input circuit of 130

the amplifier; a battery connected to the input circuit of said amplifier and in parallel to said high frequency circuit and a switch adapted, when not signaling, to impress the whole battery voltage upon the input circuit of the amplifier, whereby the space current is reduced to a minimum and adapted, when signaling, to impress a portion of said battery voltage upon the input 5 circuit of the amplifier.

5. In a high frequency signaling system, a thermionic amplifier of the audion type, a feed-back circuit inductively connected to the output circuit of said amplifier for deriving high frequency oscillations of low power from the output circuit of said amplifier, said circuit being connected to the input circuit of the amplifier; a battery connected to the input circuit of said amplifier 15 and in parallel to said high frequency circuit, and a switch adapted, when signaling, to impress a portion of the said battery voltage upon the input circuit of the amplifier and to close the feed-back circuit, and adapted, when not signaling to open the feed-back circuit and to impress the whole battery voltage upon the input circuit of the amplifier, whereby the space current in the 25 amplifier is reduced to a minimum when not 30 signaling.

6. In a high frequency signaling system, a thermionic amplifier of the audion type; a feed-back circuit inductively connected to the output circuit of said amplifier for deriving high frequency oscillations of low power from the output circuit of said amplifier, said circuit being connected to the input circuit of the amplifier, a battery connected to the input circuit of said amplifier 35

and in parallel to said high frequency circuit, 40 and a magnetically operated switch adapted, when signaling, to shunt a portion of the battery voltage upon the input circuit of the amplifier and to close the feed-back circuit, 45 and adapted, when not signaling, to open the feed-back circuit and to impress the whole battery voltage upon the input circuit of the amplifier, whereby the space current in the amplifier is reduced to a minimum when not 50 transmitting signals.

7. In a high frequency signaling system; a thermionic amplifier of the audion type; a feed-back circuit inductively connected to the output circuit of said amplifier for deriving high frequency oscillations of low power from the output circuit of said amplifier, said circuit being connected to the input circuit of the amplifier; a battery connected to the input circuit of said amplifier 55 and in parallel to said high frequency circuit; a choke coil and a resistance in series with said battery and a magnetically operated switch adapted, when signaling, to open the short-circuit, to shunt a portion of 60 said battery through said resistance, to impress the remainder of said battery upon the input circuit of the amplifier and to close the feed-back circuit, and adapted, when not signaling, to short-circuit the resistance in 65 series with said battery and to open the feed-back circuit, whereby the space current in the amplifier is reduced to a minimum when not transmitting signals.

In witness whereof, I hereunto subscribe 75 my name this 11th day of September, A. D. 1915.

EDWIN H. COLPITTS.
